Lewis J. Doolittle, ATTORNEY.

UNITED STATES PATENT OFFICE.

JULES H. VENON, OF NEW YORK, N. Y.

DESIGN FOR A GOBLET OR SIMILAR ARTICLE.

Application filed February 16, 1928. Serial No. 25,459. Term of patent 14 years.

To all whom it may concern:

Be it known that I, JULES H. VENON, a citizen of the United States, and resident of the city, county, and State of New York, have invented a new, original, and ornamental Design for a Goblet or Similar Article, of which the following is a specification, reference being had to the accompanying drawing, forming part thereof.

In the drawing is shown, in elevation, a goblet showing my new design.

The important feature of the design is the ornamentation embodied in the top part of the article and which is duplicated to extend entirely around the same.

I claim:

The ornamental design for a goblet or similar article, as shown and described.

JULES H. VENON.
